UNITED STATES PATENT OFFICE.

JOHN J. HICKEY, OF WASHINGTON, DISTRICT OF COLUMBIA.

HEDGE TRIMMER OR THE LIKE.

Application filed May 21, 1923. Serial No. 640,500.

To all whom it may concern:

Be it known that I, JOHN J. HICKEY, a citizen of the United States, residing at Washington, District of Columbia, have invented certain new and useful Improvements in Hedge Trimmers or the like, of which the following is a specification.

The invention relates to hedge trimmers, or the like, and has as an object the provision of a motor which may be carried by the person of the user and receive its power from a foot operated device, and which may be used for trimming hedges, clipping animals, polishing metal work, or the like.

15 Illustrative embodiments of the invention is shown in the accompanying drawing, in which—

Fig. 1 is a perspective view of the device as carried by the user.

20 Fig. 2 is a central vertical section through the motor.

Fig. 3 is a side elevation of the motor.

Fig. 4 is a section on line 4, 4 of Fig. 5, and

25 Fig. 5 is a central vertical section showing a modified form of the invention.

Fig. 6 is a detail, showing the inner side of the housing.

As shown, the motor is adapted to be 30 mounted upon a board or plate 10 and to be supported by a shoulder strap 11 and held against the body of the user by means of a belt 12.

As shown, the motor comprises a casing 35 13, rigidly secured to the board or plate 12, and containing a shaft 14 journaled in the board 10 and in the casing 13.

To operate the shaft 14, there is shown a 40 volute spring 15, one end of which is secured to the shaft 14, and the other end to the spring casing 16, revoluble on the shaft 14. To hold the casing 16 from revolution whereby it may act as an anchor for the action of the spring 15 while causing revolution of 45 the shaft 14, the casing 16 may be provided with ratchet teeth 17 and a pawl 18 may be mounted upon the board 10. The shaft 14 is shown as provided with a bevel gear 19, meshing with a second gear 20 journaled in 50 a gear housing 21 and located upon the end 22 of a flexible shaft 23, which shaft may be utilized to operate either hedge trimming, or clipping knives, or a polishing implement or the like.

55 In order that the flexible shaft 23 may be freely moved so as to extend in any direc-

tion, the housing 21 is shown as provided with an annular flange 24 revolving in a circular way 25, securely fastened to the casing 13.

To wind the spring 15 there is shown a chain 26 passing about a sheave 27, forming a portion of the housing of a volute spring 28, which has one end anchored to the housing and the other end anchored to a sleeve 29 rigid with the housing 13. A stirrup 30 is shown as secured to the end of the chain 26 in which a foot of the user may be placed. When the chain 26 is pulled by depression of the stirrup 30 the housing and sheave 27 will cause revolution of the spring casing 16 by means of a pawl 31 secured to the casing and coacting with ratchet teeth 32 carried by the casing of the spring 28. When the foot of the user is raised the spring 28 will wind the chain 26 upon the sheave 27 until a washer or like device 33 carried by the chain comes in contact with the edge of an opening 34 in the housing 13, through which opening the chain 26 passes.

As shown in Figs. 4 and 5, the device comprises a casing 13', which may be secured upon the plate 10 in the manner described in connection with the modification of Figs. 1, 2 and 3. The shaft 14' is journaled in the 85 plate and in the casing, and the shaft 14' carries the bevel gear 19' rigidly secured thereto. Revoluble on the shaft 14', there is shown a spring housing 35 having a series of ratchet teeth 36 extending throughout the 90 width of its periphery. A volute spring 37 is shown as connected at one end to the shaft 14', and at its other end to the spring housing 35.

To wind the spring 37 there is shown a 95 ring 38 floating about the ratchet teeth and having a sheave 39 formed in its outer periphery about which sheave a flexible element 40 is shown as passed, and having its end 41 connected to the sheave. A helical 100 spring 42 is shown secured to the ring 38 or to the end of the flexible element 40, and having its opposite end secured to the housing, as at 43. The flexible element is shown as passing through an opening in the housing, at 44, and as provided with a stirrup 45, at its free end. An obstruction, such as a washer 46, is secured to the element 40 to prevent the same being retracted into the housing to too great an extent. To prevent 105 the spring 37 from unwinding, one or more pawls 48 are secured to the housing 13' and

2
a rabbet 49 is formed in the ring 38 to receive the pawls 48 which coact with the ratchet teeth 36. To actuate the spring casing, pawls 50, mounted in recesses 51, in the ring 38, are shown, which are pressed, by means of springs 52, into contact with the ratchet teeth 36. A gear housing 21' is shown revoluble on the housing 13' in the same manner as already described in connection with Figs. 1, 2 and 3. The gear 19' is shown as of considerably greater size than the gear 20' to illustrate the fact that by using such difference of size in gears the device driven by the motor may be speeded up in any manner desired by means of properly selected gearing.

Arranged and carried as illustrated, the device may be readily transported and equipped with a suitable knife may, as above indicated, be used to trim hedges, or to clip animals, or supplied with a polishing element may be used to polish metal signs, to rub varnished or painted work, or in fact may be used wherever a transportable source of power is desired without the necessity for electrical or pneumatic connections.

Minor changes may be made in the physical embodiment of the invention without departing from its spirit.

I claim:

1. A hedge trimmer or the like comprising, in combination, a plate adapted to be supported upon the person of the user, a spring motor carried by said plate, a flexible shaft adapted to be operated by said motor, an implement upon said shaft, and means operable by the foot of the user for storing power for actuation of said motor.
2. A hedge trimmer or the like comprising, in combination, a plate adapted to be secured to the person of the user, a housing upon said plate, a spring motor within said housing, manually operated means to store energy in said motor, a beveled gear adapted to be operated by said motor, a flexible shaft provided with a bevel gear meshing

with said first named gear, a freely revoluble gear housing in which said shaft is journaled, and means operated by said shaft to utilize the power of said motor.

3. A hedge trimmer or the like comprising, in combination, a plate adapted to be attached to the person of the user, a motor housing secured upon said plate, a shaft journaled in said plate and housing, a spring casing revoluble on said shaft, a volatile spring in said casing, the ends of said spring secured to said shaft and casing respectively, a series of ratchet teeth upon the external circumference of said casing, a pawl secured to said housing, coacting with said ratchet teeth through a portion of their width, a ring surrounding said ratchet teeth, pawls carried by said ring coacting with a portion of the width of said teeth, said ring having a rabbet for clearance of said first named pawl, a sheave upon the external circumference of said ring, a flexible element coacting with said sheave passing to the exterior of said housing adapted to be manually operated by the user, resilient means restraining the revolution of said sheave by said flexible element and adapted to return the same to normal position, a bevel gear upon said shaft, a flexible shaft carrying a bevel gear coacting with said first named bevel gear, and means mounted upon said flexible shaft for utilizing the energy stored in said spring.

4. A hedge trimmer or the like comprising, in combination, a plate, a shoulder strap for supporting said plate below the arm pit of a user, a spring motor mounted on said plate, a flexible member for winding said motor and adapted to hang substantially parallel with a leg of the user, means on said member to be engaged by the foot of the user whereby treading movement of the foot may store energy in said motor and free walking movement may be had without disengaging said foot from said means.

JOHN J. HICKEY.
